UNITED STATES PATENT OFFICE

153,953

DESIGN FOR A TRAILER

Paul W. Lane, San Rafael, Calif.

Application August 19, 1947, Serial No. 140,943

Term of patent 14 years

(Cl. D14—3)

To all whom it may concern:

Be it known that I, Paul W. Lane, a citizen of the United States, and a resident of the city of San Rafael, county of Marin, State of California, have invented a new, original, and ornamental Design for a Trailer, of which the following is a specification, reference being had to the accompanying drawings, forming a part thereof.

Fig. 1 is a side elevational view of a trailer showing my new design, the sides and front being symmetrical throughout;

Fig. 2 is a side perspective view thereof;

Fig. 3 is a rear elevational view thereof; and

Fig. 4 is a front elevational view thereof.

I claim:

The ornamental design for a trailer, as shown and described.

PAUL W. LANE.
